John & Charles Willinghams of Boston Mass,
Letters Patent

It is hereby informed to the aforesaid John & Charles Willinghams of Boston in the County of Suffolk and Commonwealth of Massachusetts that the inventors of this instrument in the aforesaid City doth for avoiding fraud

To all persons to whom these presents shall come, Be it known that the John & Charles Willinghams of Boston in the County of Suffolk and Commonwealth of Massachusetts have invented a new and useful invention called a marine sounding apparatus, and that the following is a full and exact description thereof. The objects to which this apparatus can be applied are chiefly to save sunken vessels, & hence they have been denominated by the inventors, & ^{to great benefit} ~~to great hazard~~ to the public, to light them, or to shoot them out of the water for re-floating. These objects are effected by a hollow boat, or cask, filled with water, and attached to the object to be raised and then settling the water by a forcing pump from the boat, or cask, and by placing the place with air when they will rise a weight equal to the amount of water displaced. As the weight of the air, all which may be done in the following manner.

The drawing hereto annexed at plate 1 fig 1, represents a sunken ship, with a hollow boat & attached to it, to be made of wood, Indian Mallet cloth, or any durable substance. One boat is represented in the drawing as attached to the vessel, but the can be ~~and~~ attached to each side of the vessel, and even more if necessary. Fig 2 represents another boat of the same kind. These boats must be built for the purpose, of sufficient strength and tightness to be confined in safety, in the water. On a windlass, &c, or a well running through the boat, in which a cable is passed through after it has been secured the sunken ship and entangled in

in "Plate 1. Fig. 1." The cable is then made fast to the windlass
and ~~the~~ ^{and} valve B. is opened and the water let into the
Boat, at J. which is an open hole in the bottom of the boat.
The Boat can then be drawn down to the depth required. G.
is a tube which stands a little above the top of the boat, and
goes down to the bottom where it turns up with a valve
on the end opening outwards, with a valve at the upper end
C. and a force pump or bellows attached to it. Then shut
the valve C and start the pump and the air will rise from
the end of the tube G and fill the Boat with air. They
will then raise the amount of weight of the water displaced.
Another tube can be screwed on at G whenever necessary so long
on the tube. Plate 2. represents the mode of raising Ships out
of the water for repairing. A represents a ship. B. D. B. 4c
a number of round casks, or Boats of such dimensions as
may be required. These represented are supposed to be five
feet in diameter and one hundred feet long. C.C. is a platform
over these boats. Q.C. Q.G. &c are upright posts with ten-
ments into the horizontal timber which can be moved if re-
quired for a larger or smaller vessel. F.G. F.G. is a staging to
walk upon. H.G. H.G. are braces. I.M. I.M. are eas-
ily floored. D.P. D.P. are pipes, as in Plate 1 passing thru
the casks or Boats and additional tubes may be attached to
them where required as described in Plate 1. with a valve, and
force pump at the upper end of the tube. In order to
sink the casks or Boats. The air valves D.R.H. &c should
be opened and the boats, and platform will sink low-
enough to allow of their being pushed under the vessel. Then
by working the pump the air will press the water out of
J. and the ship will be hoisted out of water as represented
in Plate 2. Fig. 1. We claim as our invention and
as not having been previously used or known, the machine
or apparatus herein described, as combined together for

9268X

the purposes before mentioned? We testifying that the above
is a true specification of our said machine We have hereunto
set our hands the twenty second day of June A.D. One thousand
one hundred and thirty five
